Primary Examiner—Doris Clark*Attorney, Agent, or Firm*—Heslin & Rothenberg, P.C.[57] **CLAIM**

The ornamental design for a pool, as shown and described.

DESCRIPTION

FIG. 1 is an isometric view of one embodiment of a pool showing my new design;

FIG. 2 is a side elevational view thereof, the front, back and opposite side elevational views being identical thereto;

FIG. 3 is a top plan view thereof;

FIG. 4 is a bottom plan view thereof; and,

FIG. 5 is an isometric view of a second embodiment of a pool showing my new design. The front, back, and opposite side being identical thereto. The bottom is essentially the same as the bottom of the pool in FIG. 4.
